US0D1084581S

(12) **United States Design Patent** (10) **Patent No.:** **US D1,084,581 S**
(45) **Date of Patent:** **** Jul. 15, 2025**

(54) **SINK RACK**

(71) Applicant: **Shuai Zuo**, Hubei (CN)

CN 308877951 * 10/2024
CN 309033612 * 12/2024

(72) Inventor: **Shuai Zuo**, Hubei (CN)

(**) Term: **15 Years**

(21) Appl. No.: **29/974,895**

(22) Filed: **Nov. 26, 2024**

(30) **Foreign Application Priority Data**

May 28, 2024 (CN) 202430319730.2

(51) **LOC (15) Cl.** **07-05**

(52) **U.S. Cl.**

USPC **D32/55**

(58) **Field of Classification Search**

USPC D32/55, 56, 58, 53.1, 54; D3/304, 310
CPC .. A47L 15/505; A47L 15/503; A47L 15/0013;
A47L 19/02; A47L 19/04; A47J 47/20

See application file for complete search history.

(57) **CLAIM**

The ornamental design for a sink rack, as shown and described.

DESCRIPTION

FIG. 1 is a front, right and top perspective view of a sink rack, showing my new design;

FIG. 2 is a rear, left and bottom perspective view thereof; FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right and top perspective view of the sink rack, shown in an alternative position; and,

FIG. 10 is a rear, left and bottom perspective view thereof. The broken lines in the figures depict portions of the sink rack that form no part of the claimed design.

1 Claim, 10 Drawing Sheets
